UNITED STATES PATENT OFFICE.

MINOTT W. SEWALL, OF ROSELLE, NEW JERSEY, ASSIGNOR TO THE
BABCOCK & WILCOX COMPANY, OF NEW YORK, N. Y.

SELF-CLOSING APERTURE-COVER.

SPECIFICATION forming part of Letters Patent No. 659,000, dated October 2, 1900.

Application filed March 2, 1900. Serial No. 7,070. (No model.)

To all whom it may concern:

Be it known that I, MINOTT W. SEWALL, a citizen of the United States, residing at Roselle, in the county of Union and State of New Jersey, have invented certain new and useful Improvements in Self-Closing Aperture-Covers, of which the following is a specification, reference being had therein to the accompanying drawings.

10 This invention as herein illustrated and described is designed for use as a self-closing cleaning-door for steam-generators. The invention, however, is adapted to be used as a door, gate, or window or analogous thing to cover an aperture or opening in other structures.

The invention consists in a plate or disk of proper shape and size to cover the aperture or opening operating in a vertical or inclined 20 direction relatively to the axis of the opening and provided with fixed guideways that direct the plate and trunnions, that permit its oscillation to accommodate itself to its seat in its closing operation, and to a position to retain 25 it in place when opened, all as hereinafter particularly described, reference being had to the accompanying drawings, forming part of this specification, in which—

Figure 1 represents a vertical section of a 30 part of the inclosing side wall of a water-tube steam-generator to which the invention is applied; Fig. 2, a partial front elevation of the same; Fig. 3, a sectional plan view; Fig. 4, a vertical sectional view showing a modified construction, and Figs. 5, 6, 7, and 8 enlarged views of the invention detached and from which reference to the construction and 35 operation of the parts may be conveniently made in connection with the following description.

40 *a* is the cover or door, and *b* the aperture or opening, the cover being shown in open position in Fig. 7 and in closed position, Figs. 6 and 8.

45 *c* are trunnions, fixed to the cover or formed as an integral part thereof, which engage with ways *d d*, that guide the cover in its opening and closing movement, the opening movement being effected by lifting the cover 50 by hand or by applying a bar beneath the central lug *h*. The cover is also provided

with flanges *v v*, which bear upon the ways *d d* and serve in its movement to maintain it parallel therewith. The trunnions permit the cover to oscillate, and in its opening or 55 upward movement its upper edge *i* is brought in contact with the inclined lug *k*, which turns the cover to the position shown in Fig. 7, throwing its lower edge *m* inwardly and in connection with the projection or catch *n*, 60 which may be alone provided, as shown in Fig. 4, or formed, as shown, as an extension of the flanges *o o*. In its self-closing movement the lower edge of the cover is disengaged from the projection or catch *n* by simply 65 forcing its upper edge *i* inwardly by a light tap or blow, the cover then falling and seating itself in its closed position, as shown in Figs. 6 and 8. The face surrounding the aperture forming the seat of the cover when 70 closed is shown in this instance slightly inclined, the cover being guided thereby in its descent, and by this construction a close contact with its seat is insured.

In Fig. 4 a modified construction is shown, 75 in which the ways that guide the trunnions of the cover are inclined and the inclined lug *k* is omitted. The cover in this construction is seated in a relatively vertical position, as shown in said figure. This modification 80 presents a mere transposition of details in the construction which may be desired in the use of the invention in other situations.

The device, as heretofore described, may be applied as a door, gate, window, or for other 85 use to which it may be adapted. Its particular adaptation as a cleaning-door for steam-generators is shown in Figs. 1 to 4, it being applied within a casing *5*, set in the side wall *t* of the generator, a series of covers and 90 openings *w* being in this instance shown arranged on a plane with the spaces between the tubes of the generator, which are placed in the semicircular recesses *x*. (Shown in Figs. 1 and 4.) The casing *5* and also the lining *z* 95 of the wall of the generator are constructed with flaring sides, as shown in Figs. 2 and 3, to obtain greater sweep of operation among the tubes with a cleaning-tool or in the introduction of a blast or other known cleaning 100 expedient.

Having thus fully described my invention,

what I claim, and desire to secure by Letters Patent, is—

1. A self-closing aperture-cover consisting of a pivotal plate or disk, engaging with suitable fixtures to guide and retain it, and movable in a vertical or inclined direction, substantially as set forth.
2. A self-closing aperture-cover consisting of a pivotal plate or disk engaging with suitable fixtures to guide and retain it, movable in a vertical or inclined direction, and seated upon an aperture-face at an angle to its direction of movement, substantially as described.

3. A cleaning-aperture for steam-generators located in its inclosing walls, constructed with flaring sides, as shown, and fitted with one or more pivotal self-closing doors, movable in a vertical or inclined direction and engaging with suitable fixtures to guide and retain the same, substantially as described. 15
20

In testimony whereof I affix my signature in presence of two witnesses.

MINOTT W. SEWALL.
